US0D1034645S

(12) United States Design Patent (10) Patent No.: US D1,034,645 S
(45) Date of Patent:  Jul. 9, 2024

(54) DISPLAY SCREEN OR PORTION THEREOF WITH GRAPHICAL USER INTERFACE

(71) Applicant: Samsung Electronics Co., Ltd., Suwon-si (KR)

(72) Inventors: Ye-Rin Park, Suwon-si (KR); Yeon-Ee Choi, Suwon-si (KR); Jae Ik Lee, Suwon-si (KR); Yeo-Jun Yoon, Suwon-si (KR); Soo-Jung Lee, Suwon-si (KR); Yong-Yeon Lee, Suwon-si (KR)

(73) Assignee: SAMSUNG ELECTRONICS CO., LTD., Gyeonggi-Do (KR)

() Term: 15 Years

(21) Appl. No.: 29/830,774

(22) Filed: Mar. 15, 2022

CLAIM

The ornamental design for a display screen or portion thereof with graphical user interface, as shown and described.

DESCRIPTION

The outermost broken lines illustrating portions of a display screen or portion thereof form no part of the claimed design. The remainder of the broken lines illustrating portions of the graphical user interface forms no part of the claimed design.

1 Claim, 1 Drawing Sheet
